UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

TRAIN-SPEED-CONTROL APPARATUS.

Application filed February 25, 1922. Serial No. 539,287.

To all whom it may concern:

Be it known that I, CLYDE C. FARMER, a citizen of the United States, residing at Pittsburgh, in the county of Allegheny and 5 State of Pennsylvania, have invented new and useful Improvements in Train-Speed-Control Apparatus, of which the following is a specification.

This invention relates to automatic train 10 speed control apparatus for controlling the speed of the train according to the indication received from the trackway.

In some cases, the regulations require that 15 a train receiving a low speed or danger indication shall be brought to a stop instead of merely having the speed reduced to the low speed limit and in order to accomplish this result, the principal object of my invention is to provide a train speed control apparatus 20 in which means are provided for bringing the train to a stop unless the engineer reduces the speed of the train practically to zero, say one mile per hour, upon receiving a danger indication from the trackway.

25 In the accompanying drawings; Fig. 1 is a diagrammatic sectional view of a train speed control apparatus embodying my invention and showing the parts in the positions assumed when receiving a high speed indication from the trackway; and Fig. 2 30 a similar view, showing the parts in the positions assumed when a low speed indication is received.

35 My invention is shown in the drawings as applied to a speed control equipment of the character disclosed in the pending application of T. H. Thomas, Serial No. 531,676, filed January 25, 1922, only so much of the speed control apparatus being shown, however, as deemed necessary to a clear understanding of the construction and operation 40 of my improvement.

45 The speed control apparatus may comprise an automatic brake valve device 1, a main reservoir 2, and a speed controlled valve mechanism.

50 The speed controlled valve mechanism may comprise a brake application valve device 3, a change speed valve device 4, a stop piston 5 and valve 6, a selector valve device 7, a medium speed valve device 8, a speed governor portion 9, a high speed magnet 10 for operating a double beat valve 11, a medium speed magnet 12 for operating

a double beat valve 13, a medium to low speed blow down valve piston 14 and valve 15, a stop reservoir 16, a medium to low speed blow down reservoir 17, a feed valve device 18, and a feed valve reservoir 19.

55 The application valve device 3 may comprise a piston 20 contained in piston chamber 21 and a slide valve 22 contained in valve chamber 23 and adapted to be operated by piston 20. The change speed valve device 4 comprises differential piston heads 24 and 25 contained in the respective piston chambers 26 and 27 and a slide valve 28, contained in valve chamber 29, and adapted to be operated by the differential pistons. The selector valve device 7 comprises a piston 30 60 contained in piston chamber 31 and a slide valve 32, contained in valve chamber 33, and adapted to be operated by piston 30. The medium speed valve device 8 comprises a piston 34, contained in piston chamber 35, 65 and a slide valve 36, contained in valve chamber 37, and adapted to be operated by piston 34.

70 The speed governor portion 9 comprises governor balls 38, operatively connected to a governor shaft 39, which is rotated according to the speed of the train by means of bevel gears 40, said gears being operatively connected to a driving axle of the locomotive. As the governor balls 38 fly out, 75 according to the speed of the train, a sliding spindle 41 having a crosshead 42 is shifted 80 so as to operate valves through which the speed of the train is controlled.

85 While the crosshead 42 is adapted to 90 operate a plurality of valves for determining the high, medium, and low speed limits of the train, as in the pending application of T. H. Thomas, hereinbefore referred to, for the purpose of illustrating the operation of 95 the present invention, it is only deemed necessary to show the low speed application valve 43 and the medium to low speed blow down timing valve 44, adapted to be operated by said crosshead.

100 According to my invention, an additional speed governor 45 is provided, comprising a rotatable governor ball carrier 46 having a stem 47 provided with a pinion 48 which is adapted to mesh with an internal gear 49 associated with one of the bevel gears 40, so that the carrier 46 is rotated according to the speed of the train. Internally, the 105

carrier 46 is provided with pockets having slightly inclined floors 50 upon which rest the governor balls 51, so that when the speed of rotation of the carrier exceeds a predetermined degree, the balls will be thrown out by centrifugal force and when the speed is below a predetermined degree, the balls will roll down the inclined floors 50 by gravity toward the axis of the governor.

10 Mounted axially in the carrier 46 is a block of insulation 52 having radial apertures in alignment with the balls 51 for receiving contact balls 53. An axially mounted contact rod 54 extends into an axial socket 15 in the insulating block 52 and separated therefrom by suitable insulation is a contact member 57 in the form of a sleeve, which is connected to a conductor post 56. The lower end of the rod 54 is provided with a head 20 58 so arranged that when the contact balls 53 are forced inwardly toward the axis, said balls will electrically connect the contact sleeve 57 through the head 58, with the rod 54. Engaging the contact balls 53 are balls 25 59 of insulation material, which are adapted to be engaged by the governor balls 51 when the balls roll toward the axis upon the train speed reducing to a predetermined degree, and this causes the contact balls 53 to be 30 forced into the position for connecting the head 58 with the contact sleeve 57. The governor above described is not claimed per se in this application, but is the subject of a co-pending application, Serial No. 539, 35 286, filed February 25, 1922.

The contact rod 54 is electrically connected to a magnet 60 and the post 56 to a source of current, so that when the circuit is closed through the action of the governor, the magnet 40 60 will be energized.

The magnet 60 operates a valve 61 for effecting the resetting of the apparatus so that the brakes can be released, as will be hereafter described.

45 In operation, when the train is receiving a high speed indication, the high speed magnet 10 will be energized, and the medium speed magnet 12 deenergized, and the system will be charged with fluid under pressure as 50 follows: Fluid under pressure will flow from the main reservoir 2 through passages 62, 63, and 64 to valve chamber 33 of the selector valve device 7 and thence through the feed groove around piston 30 to piston 55 chamber 31, thus permitting spring 65 to move piston 30 to its inner position. Fluid also flows to valve chamber 37 of the medium speed valve device 8, through passages 64 and 66 and piston 34 will then be shifted to 60 its outer position, since piston chamber 35 is open to the atmosphere through passage 67 past the double beat valve 13 of magnet 12 to exhaust port 68. Fluid also flows to piston chamber 26 of the change speed valve 65 device 4 through passage 62 past the double

beat magnet valve 11, passage 70, cavity 69 in slide valve 32 and passage 71 and fluid under pressure is supplied to piston chamber 27 from valve chamber 33 through passage 72. The valve chamber 29 of the change speed valve device 4 as well as valve chamber 23 of the application valve device 3 are charged with fluid from passage 64, through a passage 73.

From valve chamber 23, fluid equalizes 75 through a restricted port in piston 20 to piston chamber 21, permitting the spring 74 to shift the piston 20 to its inner position.

The feed valve device 18 supplies fluid 80 from the main reservoir 2 at a reduced pressure to the feed valve reservoir 19 and fluid from said reservoir is supplied to the seated area of the medium to low blow down valve piston 14 through passage 75.

When a caution or medium speed indication is received by the train, the medium speed magnet 12 will be energized and the high speed magnet 10 deenergized. The double beat valve 13 is then operated so that 90 fluid under pressure is supplied to the piston chamber 35 of the medium speed valve device 8. The spring 76 then shifts the piston 34 to its inner position and the stop reservoir 16 is charged with fluid under pressure from 95 the valve chamber 37 through cavity 77 in slide valve 36 and passage 78. As in the application of T. H. Thomas hereinbefore referred to, if the caution indication has been acknowledged, the piston 30 of the selector 100 valve device 7 will be shifted to its outer position and maintained in that position so long as the high speed magnet remains deenergized, since the piston chamber 31 is connected to the atmosphere through passage 79, cavity 80 in selector slide valve 32, 105 passage 70 and past the double beat valve 11 to exhaust port 81.

Considering first the case where the train receives a danger indication and the engineer 110 fails to reduce the speed of the train to one mile per hour or the low speed at which the speed governor 45 may be set. Both the high speed and medium speed magnets 10 and 12 will be deenergized, and as shown in Fig. 2 115 of the drawings, the deenergization of the medium speed magnet 12 will be effective to vent fluid from the piston chamber 35 of the medium speed valve device 8 through passage 67 to exhaust port 68. The piston 34 is then shifted to its outer position, in which the spring side of the medium to low speed blow down valve piston 14 is connected to the blow down timing valve 44 through passage 103, cavity 104 in slide valve 36, and 120 passage 105, and the medium to low speed blow down reservoir 17 being also connected to the spring side of the valve piston 14 through passage 82, fluid will be vented from 125 the reservoir 17 and the spring side of the 130

valve piston 14 at a rate corresponding with the size of the vent opening created by the valve 44, which in turn depends upon the rate of speed of the train.

- 5 When the pressure in the reservoir 17 and on the spring side of the valve piston 14 has been reduced to a predetermined degree, the feed valve pressure acting below the valve piston 14 will shift same to its 10 upper position, as shown in Fig. 2, thus opening the valve 15. Fluid under pressure will then be vented from the piston chamber 26 of the change speed valve device 4 through passage 71, cavity 69 in selector 15 slide valve 32, passage 83, cavity 84 in medium speed slide valve 36, passage 85, and past the valve 15 to exhaust port 86.

The change speed valve device will then be shifted to the low speed position, due to 20 its differential piston construction. In this position, the piston chamber 87 of the stop piston 5 is connected to the stop reservoir 16 through passage 78, cavity 77 in medium speed slide valve 36, passage 88, cavity 89 25 in selector slide valve 32, passage 90, cavity 91 in change speed slide valve 28, and passage 92. Since the stop reservoir 16 was previously charged with fluid under pressure in the medium speed position of the 30 parts, fluid is supplied to stop piston 5, operating the same to open valve 6 and thereby vent fluid from piston chamber 21 of the application valve device 3, through passages 93 and 94 to exhaust port 95.

35 The application piston 20 is then shifted to its outer position, in which the slide valve 22 connects the usual brake pipe 96 with the exhaust, through a cavity 97. The reduction in brake pipe pressure thus produced 40 effects an application of the brakes in the usual manner and the train will be brought to a stop.

When the speed of the train has been reduced to one mile per hour or less, in the 45 above described operation, the governor balls 51 of the speed governor 45, at this low speed will roll down the inclines 50, by gravity, toward the axis of the governor and will then force the balls 59 and 53 inwardly, so that the contact balls 53 will 50 close the circuit of the reset magnet 60. The energization of magnet 60 operates to open the valve 61 and vent fluid from the stop reservoir 16, by way of passage 78, cavity 77 in medium speed slide valve 36, passage 88, cavity 89 in selector slide valve 32, passage 90, and past the open magnet valve 61 to exhaust port 101.

60 The venting of fluid from the stop reservoir 16 as above described, causes fluid to be vented from piston 5, so that the valve 6 and piston 5 will be moved to the closed position by spring 98, thus cutting off the 65 venting of fluid from the application piston 20.

The brakes may now be released by operating the brake valve 1, so as to lap the port leading to the release pipe 102. The piston chamber 21 of the application piston 20 being connected in the application position 70 of slide valve 22 through passage 93 and cavity 106 with the release pipe 102, fluid under pressure will now equalize on opposite sides of the application piston 20 through the restricted port in said piston. Spring 74 will then return piston 20 and slide valve 22 to release position, permitting the brakes to be released by the usual operation of the brake valve 1.

If the engineer applies the brakes as soon 80 as a low speed signal indication is received and the speed of the train is thus reduced to one mile per hour during the time interval before the speed control parts are shifted to the low speed position, the magnet 85 60 will be energized by operation of the governor 46 so as to open the valve 61 and thereby effect the venting of fluid from the stop reservoir 16. It will thus be seen that 90 when the speed control parts move to low speed position after the expiration of the time interval, the pressure in the stop reservoir having been vented, the piston 5 will not be operated to open the valve 6 and consequently the application valve device 3 95 will not be operated to effect an application of the brakes.

After the brakes have been released, the 100 train may proceed while the signal indication is set at low speed, if the speed is not allowed to exceed the low speed limit at which the low speed valve 43 is opened by operation of the speed governor 9. If the speed should be increased above the low 105 speed limit, the valve 43 will be unseated, so as to vent fluid from the application piston 20 and thus cause an application of the brakes.

Having now described my invention, what 110 I claim as new and desire to secure by Letters Patent, is:—

1. In a train speed control apparatus, the combination with means for imposing a predetermined low speed limit on the train, of means effective in the low speed position of the apparatus for imposing a still lower speed limit on the train.

2. In a train speed control apparatus, the combination with means for imposing a predetermined low speed limit on the train, of mechanism effective in the low speed position of the apparatus for imposing a much lower speed limit on the train and speed controlled means operative at the lower speed limit for rendering said mechanism ineffective.

3. In a train speed control apparatus, the combination with means for imposing a predetermined low speed limit on the train, of mechanism effective in the low speed posi-

tion of the apparatus for imposing a speed limit less than said predetermined low speed limit on the train and speed controlled means operative at the lower speed limit 5 for rendering said mechanism ineffective, thereby permitting the train to proceed at said predetermined low speed limit.

4. In a train speed control apparatus, the combination with means operative upon receiving a low speed indication for bringing the train to a stop, of means operative in advance of receiving a low speed indication for preventing the operation of said train stopping means when the speed of the train 10 does not exceed a predetermined limit and means for then imposing a low speed limit which is higher than said predetermined speed limit.

5. In a train speed control apparatus, the combination with means operative when the train receives a low speed indication for bringing the train to a stop, of means for rendering said means ineffective, if the engineer reduces the speed of the train to a predetermined degree lower than the low speed limit.

6. In a train speed control apparatus, the combination with a reservoir charged with fluid under pressure and means operated by fluid from said reservoir for bringing the train to a stop, of means governed by the speed of the train and operative upon a reduction in the train speed to a low degree for venting fluid from said reservoir.

35 7. In a train speed control apparatus, the combination with a valve device for effecting an application of the brakes, a valve for controlling the operation of said valve device, and a piston for operating said valve, of a reservoir charged with fluid under pressure, means for supplying fluid from the reservoir to said piston, a speed controlled governor, and means controlled by said governor for venting fluid from said reservoir.

45 8. In a train speed control apparatus, the combination with a valve mechanism operated by fluid under pressure for effecting an application of the brakes, of a reservoir charged with fluid under pressure, means operative upon receiving a low speed indication for supplying fluid from the reservoir to said valve mechanism, means for venting fluid from said reservoir, and a governor controlled by the speed of the train for controlling the operation of said means.

60 9. In a train speed control apparatus, the combination with a reservoir charged with fluid under pressure, of a magnet, a valve operated by said magnet for venting fluid from said reservoir, and a speed controlled governor operative at a predetermined low train speed for controlling the circuit of said magnet.

65 10. In a train speed control apparatus, the combination with an application valve

device operated upon a reduction in fluid pressure for effecting an application of the brakes, of a valve for venting fluid from said valve device, a piston operated by fluid under pressure for operating said valve, a reservoir from which fluid is supplied to said piston, a magnet, a valve operated by said magnet for venting fluid from said reservoir, and a speed controlled governor operative at a predetermined low train speed for closing the circuit of said magnet. 70 75

11. In a train speed control apparatus, the combination with a reservoir charged with fluid under pressure, a valve mechanism operated by fluid from the reservoir for effecting an application of the brakes, and means operative upon receiving a low speed indication for connecting said reservoir with said valve mechanism, and a speed controlled mechanism operative at a predetermined speed less than the low speed limit for venting fluid from said reservoir. 80 85

12. The combination with a train speed control apparatus including means for setting said apparatus for different speed limits, of a reservoir adapted to be charged with fluid under pressure when the control apparatus is set for one speed limit, means operated by fluid from said reservoir for effecting a reduction in the speed of the train, and means operative upon a predetermined reduction in the speed of the train for venting fluid from said reservoir. 90 95

13. The combination with a train speed control apparatus including means for setting said apparatus for high, medium, and low speeds, of a reservoir adapted to be charged with fluid under pressure when the control apparatus is set for medium speed, means operated by fluid from said reservoir for effecting a reduction in the speed of the train, and means operative upon a predetermined reduction in the speed of the train for venting fluid from said reservoir. 100 105

14. The combination with a train speed control apparatus including means for setting said apparatus for high, medium, and low speeds, of a reservoir adapted to be charged with fluid under pressure only when the control apparatus is set for medium speed and means operated by fluid from said reservoir for effecting a reduction in the speed of the train. 110 115

15. The combination with a train speed control apparatus having means for setting said apparatus for high, medium, and low speeds, of a source of fluid under pressure, a valve device operated by fluid under pressure for effecting an application of the brakes, a reservoir, and means for connecting said reservoir to the atmosphere in the high speed position, to said source of fluid pressure in the medium speed position, and to said valve device in the low speed position. 120 125 130

16. The combination with a train speed control apparatus having means for setting said apparatus for high, medium, and low speeds, of a source of fluid under pressure, a valve device operated by fluid under pressure for effecting an application of the brakes, a reservoir, means for connecting said reservoir to said source of fluid pres-

sure in the medium speed position and to said valve device in the low speed position, 10 and means controlled by the speed of the train for venting fluid from said reservoir.

In testimony whereof I have hereunto set my hand.

CLYDE C. FARMER.
